CLAIM

The ornamental design for a wall lamp, as shown and
described.

DESCRIPTION

1. Wall lamp
- 1.1 : Perspective
- 1.2 : Front
- 1.3 : Right
- 1.4 : Top
- 1.5 : Left
- 1.6 : Bottom
- 1.7 : Back

The name of the claimed design product: wall lamp; the
purpose of the claimed design product: for illuminating
purposes; the relevant feature of the claimed design product:
the shape of the product; picture or photograph that best
illustrates the main point of the design: figure 1.1; figure 1.1
is a front perspective view of a lamp; figure 1.2 is a front
view thereof; figure 1.3 is a right-side view thereof; figure
1.4 is a top view thereof; figure 1.5 is a left-side view
thereof; figure 1.6 is a bottom view thereof; figure 1.7 is a
back view thereof; the parts of the lamp shown by means of
broken lines in the reproductions are not part of the claimed
design.
